UNITED STATES PATENT OFFICE.

GEORGE C. LASARES, OF SPRINGFIELD, MASSACHUSETTS.

GAME APPARATUS.

1,087,956.

Specification of Letters Patent.

Patented Feb. 24, 1914.

Application filed June 25, 1912. Serial No. 705,723.

To all whom it may concern:

Be it known that I, GEORGE C. LASARES, a citizen of the United States, residing at Springfield, in the county of Hampden and 5 State of Massachusetts, have invented new and useful Improvements in Game Apparatus, of which the following is a specification.

This invention relates to improvements in 10 game apparatus or devices of the type in which, when a ball is rolled along the floor or alley and the target is struck by the same, a number is caused to appear through a suitable opening in the device.

15 The invention consists broadly of a pivoted member, adapted to be struck by the rolled ball, for releasing a member which carries the number, the number bearing device being automatically drawn upward 20 when released.

The invention further consists in devices for resetting the numbers in their original position prior to a second bowling during the playing of the game.

25 Referring to the drawings: Figure 1 is a front elevation of the device illustrating two pendant members that are adapted to be struck by the rolled ball and the openings through which the numbers appear when 30 one or both of the pendant devices is struck by the rolled ball. Fig. 2 is a transverse sectional view on the line 2—2 of Fig. 1 showing in detail the latch mechanism by means of which the slide which carries the numbers

35 or figures is retained in its locked position, and also the devices for resetting the slide devices which bear the numbers.

Referring now to the drawings in detail, *a* designates the standards or uprights which 40 support the device and *b* the foot members to which the uprights are secured.

c designates a member that extends across from one of the uprights to the other and which is suitably secured thereto. This 45 member is formed with openings *d* therein through which the numbers on a slide member show.

f designates a pendant member adapted to be struck by the rolled ball. This pendant member is provided with a projection or rod *g* on the rear side thereof. The pendant member *f* is connected to a pivotally mounted latch member *h* by means of a hinge connection as shown at *i*. The latch member *h* is pivotally mounted on a rod *j* 55 that extends from one upright to the other.

The latch member *h* is normally drawn inward toward the upright *a* by means of a spring *l* which is attached to a bar *m* at one end and to the latch member *h* at the 60 other end. The latch member *h* is provided with a catch or lip device *o*, which is adapted to engage a similar device *p* on the slide *q*. This slide device is mounted for movement in the guideways *r*. Attached 65 to the upper end of the slide device *q* is a spring *s*, its upper end being secured to a longitudinally arranged bar *t* as shown in the figures. This spring normally tends to move the slide *q* upward when released by 70 the latch member *h* after being struck by the projection *g* of the pendant member *f*.

Referring now to the operation of this 75 part of my device: When a ball is rolled against the pendant member *f* the projection *g* will follow the path shown by the dotted line *u*, which in turn will strike the latch member *h* and rotate the same about its pivot *j*, causing the parts *o* and *p* to separate. The spring *s* will then immediately 80 pull the slide *q* upward and bring the number which is mounted on the particular slide opposite the opening *d*, the number being secured to the slide member *q* at the part designated *w*. It is, of course, obvious that 85 should the ball, shown in dotted lines *x*, strike two of the pendant members *f* the numbers on two of the sliding members *q* will be simultaneously exposed before the 90 openings *d*.

In order to reset the device prior to the 95 rolling of the ball the second time after all of the numbers have been exposed, a push rod *y* is provided having a thumb piece *z* secured at its upper end. This rod is secured to the bar *4* by means of a pin *4¹*. The rod *y* passes loosely through a bracket *5* that is attached to the sliding member *q* by means of a pin *q¹*, so that when the thumb piece *z* is pushed downward from its dotted 100 line or elevated position to its full line position all of the sliding members *q* will be reset at the same time by reason of the bar *4* engaging all of the brackets *5*, *i. e.* the parts *o* and *p* will be latched together, it being understood that the pendant and latch members *f* and *h* have again returned to their original position, as shown in the figures.

It will be noticed that the pendant member *f* by reason of its pivotal connection 110 with the latch member *h* automatically swings backward to its vertical position as

shown in Fig. 2 and that such a construction prevents the ball α shown in dotted lines in Fig. 1 from becoming wedged or caught under the pendant member. This is a very important feature of my improvement.

Located at the opposite ends of the bar 4 is a guide rod 4² which is suitably secured to the bar t as shown at 4³.

What I claim, is:

10 1. As an improvement in game devices, the combination with the standards thereof, of pendant members adapted to be struck by a rolled ball, rods secured to said members, latch members to which the pendant members are secured and which are adapted to be operated by the rods on the pendant members, sliding members, latch devices on the sliding members and adapted to be released by the latch members, and means to move the sliding members upward after being released by the latch members.

25 2. As an improvement in game devices, the combination with the standards thereof, of pendant members adapted to be struck by a rolled ball, striking devices carried by said members, latch members to which the pendant members are secured and which are adapted to be operated by said devices on the pendant members, sliding members, latch devices on the sliding members and adapted to be released by the latch members, when the latch members are engaged by the striking devices, means for moving the sliding members upward after being released, and

35 3. In a game device of the kind described, a latch member pivotally mounted for swinging movement, a pendant member pivotally connected to the latch member, a projection on the pendant member and adapted to operate the latch member when struck by a rolled ball, a sliding member being adapted to be released by the latch member to

bring a number thereon before a suitable 45 opening, said opening being located in a part that extends longitudinally of the device, and means for resetting the sliding member.

4. In a bowling device of the kind described, in combination, upright members, a longitudinal member secured thereto and provided with openings therethrough, pendant members, projections secured to the pendant members, latch members to which the pendant members are pivoted, means for holding the latch members in locking positions, sliding members adapted to be drawn upward past the openings in the longitudinal member, projections secured to the sliding members, a bar located above the projections, a push rod secured to and passing through the bar, whereby after the sliding members have been unlatched by a rolled ball the sliding members can be reset as described.

5. In a bowling device of the kind described, in combination, upright members, a longitudinal member secured thereto and provided with openings therethrough, a 70 pendant member, a projection secured to the pendant member, a latch member to which the pendant member is pivoted, means for holding the latch member in a locking position, a sliding member adapted to be drawn 75 upright past the opening in the longitudinal member, a projection secured to the sliding member, a bar located above the projection, a push rod passing through the bar and secured thereto, whereby after the sliding member has been unlatched by a rolled ball the sliding member can be reset as described, and whereby the pendant member will prevent the ball from being caught.

GEORGE C. LASARES.
